UNITED STATES PATENT OFFICE.

HERMAN HILENBURG, OF PHILADELPHIA, PENNSYLVANIA, ASSIGNOR TO
THE MACKELLAR, SMITHS & JORDAN COMPANY, OF SAME PLACE.

DESIGN FOR TYPE.

SPECIFICATION forming part of Design No. 16,715, dated June 1, 1886.

Application filed April 29, 1886. Serial No. 200,630. Term of patent 14 years.

To all whom it may concern:

Be it known that I, HERMAN HILENBURG, (assignor to the MACKELLAR, SMITHS & JORDAN COMPANY.) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of an unshaded ornamental letter provided with the curved line with dot termination, as shown—in the A at the upper left-hand corner, in the B and C in the upper rounding portion, in the D in the lower rounding portion, in the E, F, G, L, N, P, R, S, T, V, W, and Z upon the right, and in the S, T, Y, and Z upon the left, as shown. The central ornament of the A, F, and H consists of the two inclined lines with space between, provided about centrally with the triangular ornament. The cross ornament of the E consists of the two inclined lines having the triangular ornament upon the right. The O and Q are ornamented upon the face by the inclined lines with space between. The M is ornamented by the curved line with dot termination crossing its intermediate up-and-down portion. The A and M are extended below the line upon the left.

The character of the design is preserved in the lower-case.

In connection with the font are shown three typographic adjuncts. The first consists of a heavy central dot, from which radiate a series of short lines with dot termination. The second consists of a dot placed in the center of a circle, from the exterior of which extend the short lines with spear-head-like ornaments, the upper and lower central ones being followed by a second line terminating in the dot, as shown; and the third consisting of the rhomboidal figure having the heavy dots

placed outside it and in line with the points at which the lines forming it meet.

Having now set forth my invention, I claim as new—

The design for a font of printing-type, as shown, the same consisting of an unshaded ornamental character provided with the curved line with dot ornamentation, as shown—in the A at the upper left-hand corner, in the B and C in the upper rounding portion, in the D in the lower rounding portion, in the E, F, G, L, N, P, R, S, T, V, W, and Z upon the right, and in the S, T, Y, and Z upon the left, the central ornament of the A, F, and H consisting of the two inclined lines with space between, provided about centrally with the triangular ornament, the cross ornament of the E consisting of the two inclined lines having the triangular ornament upon the right, the O and Q ornamented upon the face by the inclined lines with space between, the M ornamented by the curved line with dot terminations crossing its intermediate up-and-down portion, the A and M extended below the line upon the left, the character of the design being preserved in the lower-case, and the font provided with the typographic adjuncts, the first consisting of a heavy central dot, from which radiate a series of short lines with dot termination, the second of a dot placed in the center of a circle, from the exterior of which extend the short lines with spear-head-like ornament, the upper and lower central ones being followed by a second line terminating in the dot, as shown, and the third consisting of the rhomboidal figure having the heavy dots placed outside it and in line with the points at which the lines forming it meet.

HERMAN HILENBURG.

In presence of—

C. F. HUCH,
HERMAN METIUS.
